CLAIM

I claim the ornamental design for an optical adapter for mobile device, as shown and described.

DESCRIPTION

U.S. Utility patent application Ser. No. 12/459,375, entitled “Optical Adapters for Mobile Devices with a Camera,” filed concurrently on Jun. 29, 2009.

U.S. Design patent application Ser. No. 29/315,497, entitled “Case for Optical Adapter and Mobile Device,” filed concurrently on Jun. 29, 2009.

U.S. Design patent application Ser. No. 29/312,498, entitled “Case for Optical Adapter and Mobile Device,” filed concurrently on Jun. 29, 2009.

U.S. Design Patent Application Ser. No. 29/315,500, entitled “Case for Optical Adapter and Mobile Device,” filed concurrently on Jun. 29, 2009.

FIG. 1 is a perspective view of an optical adapter for mobile device showing my new design;

FIG. 2 is a back view thereof;

FIG. 3 is a front view thereof;

FIG. 4 is a right view thereof;

FIG. 5 is a left view thereof;

FIG. 6 is a top view thereof; and,

FIG. 7 is a bottom view thereof.

My optical adapter for mobile device is characterized by:

a) a generally cylindrical shape substantially flattened on one side to mate with a surface of a mobile device,

b) a substantially rounded bottom end which has a substantially vertical opening in the flattened side for aligning with a camera lens on the mobile device, and

c) a substantially rounded top end which has a vertical opening in the flattened side for allowing light to enter the optical adapter over the edge of the mobile device,

wherein the rounding on the top and bottom follow a substantially symmetrical curve.
